SYLVESTER M. SCHWELLER, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed October 26, 1927. Serial No. 228,918.

This invention relates to improvements in refrigerating apparatus and more particularly in the cooling elements adapted for use in mechanical refrigerators.

5 It is an object of the invention to provide an improved refrigerating element capable of being used in lieu of blocks of ice in refrigerators.

More specifically, it is among the objects 10 of the invention to provide an improved refrigerating element of the type including finned refrigerant conveying ducts, in which the heat absorbing surfaces of the element are arranged to insure free circulation of air 15 about the fins, and arranged so that the fins can be readily attached to the ducts, and so arranged that the entire surface of the fin is efficiently cooled.

Further objects and advantages of the 20 present invention will be apparent from the following description, reference being had to the accompanying drawing, wherein a preferred form of the present invention is clearly shown.

25 In the drawings:

Fig. 1 represents a side view in cross section of a display case refrigerator equipped with the refrigerating element of the invention;

30 Fig. 2 is a top view of the refrigerating element, and

Fig. 3 is a side view of the same.

Referring in detail to the drawings the refrigerating element or cooling unit comprises 35 a header or tank 10 which in the type of refrigerating system selected for illustrating the preferred embodiment of the invention serves as a means for receiving a refrigerating medium, preferably in liquid form, e. g., sulfur dioxide, and for distributing the same to the other parts of the apparatus.

The refrigerating medium is led into the header 10 through duct 11. A suitable form of float valve, not shown, may be used to maintain a constant level of refrigerant in the header. The vaporized refrigerant is led off from said tank through duct 12 which leads off from the space above the liquid level in the header.

40 The header is provided with a plurality of

cooling coils consisting essentially of a plurality of dependent ducts or loops of pipe. These loops will be considered as constituting two series of loops, each including a plurality of sets of loops. One series of loops, 55 referred to as series 13—14, comprises a plurality of sets of loops, each set including a loop 13 and a loop 14. Another series, referred to as series 15—16, comprises a plurality of sets of loops, each set including a 60 loop 15 and a loop 16. The loops are connected in parallel to the header below the liquid level therein and depend below into the air cooled by said refrigerating element. The ducts are preferably flattened in their 65 dependent portion to facilitate attachment of fins and to increase their radiating surface while decreasing the refrigerant space.

Of the series 13—14, each loop 13 has a vertical leg 13' (Fig. 3) depending downwardly 70 substantially adjacent the vertical axis of header 10, and a second vertical leg 13'' which is offset laterally a considerable distance from the same axis and which also depends downwardly from the header.

75 The other loops of the series 13—14 are indicated by the numeral 14; each loop has a vertical leg 14' depending downwardly but laterally offset from the header. The second vertical leg 14'' of this loop depends downwardly substantially adjacent the vertical axis of header 10. The loop series 15—16 has loops 15 of which a vertically depending leg 15' is offset laterally from the header to a greater extent than leg 13' but not as much as leg 14' so that leg 15' in effect is really intermediate legs 14' and 13'. The other leg 15'' of loop 15 is disposed adjacent the header 10. Leg 15'' is in the same plane as leg 14'' and is therefore not visible in Fig. 3, although its top is shown in Fig. 2. Each loop 16 of series 15—16 likewise has a leg 16' disposed laterally offset to the header but not to the same degree as leg 13''; leg 16' may therefore be said to be intermediate legs 14'' 85 and 13''. The other leg 16'' of loop 16 extends vertically in the same manner on the opposite side of the header and is disposed the same distance from the vertical axis of the header as leg 15''. It is not visible in Fig. 3 90

95

100

although its top is indicated by 16" in Fig. 2.

It will be observed that all of the loops marked 13 and 14 are bent up in the same shape but when they are attached to the header 10 alternate loops of a set are turned reversely so that the laterally offset legs 13" and 14' project alternately on opposite sides of the header.

Of the loop sets 13—14, each has a copper fin 17 attached thereto as by soldering or the like so as to insure good thermal connection between the loop and fin. Preferably the fins are soldered to the legs 13" and 14' at approximately the central portion of the fins

15 The most laterally offset loops 13" and 14' are preferably held in spaced relation by means of tie bars 18 which are soldered to the bottom of the loops. The less laterally disposed loops 14" and 13' are held in a sufficiently rigid manner being substantially in the center of the fin where they are subjected to less bending strain. Tie bars 19 may be used to keep the outer edges of the fins held in spaced relation.

20 25 It is thus apparent that the refrigerating element comprises a header, and a plurality of sets of dependent loops and fins, the fins being attached to the sets having loops extending the greatest distance laterally either 30 side of the header. The space between the parallel dependent loop sets 13—14 is therefore occupied by a set of loops which bear no fins and the legs of which are not extended laterally offset from the header to the same 35 extent as the legs to which the fins are attached.

It is also apparent that the loops of a given set are located in substantially the same plane, extending on either side of the header,

40 45 A single fin made of a plane sheet of metal may therefore be attached to both loops and preferably by soldering or otherwise uniting in good thermal contact the loop at one side of the header to one side of the fin and the loop at the other side of the header to the other side of the same fin. This construction facilitates assembly and imparts a symmetrical appearance and balance to the apparatus while obviating the use of a plurality of fins.

50 55 In the operation of the refrigerating element the refrigerating medium in the vertically dependent legs absorbs heat from the circulating air and hence serves to cool the same. The fins aid in increasing the effective surface of the loops and direct the air currents. Due to moisture in the circulating air the loops and fins may become coated with frost which, if the fins are too closely spaced may bridge over between the fins, joining 60 them with a network of ice which will hinder or prevent circulation of the air. By providing an intermediate set of loops e. g., the set 15—16 without fins this disadvantage is obviated. The fins are thus maintained at a 65 suitable distance from each other while the

refrigerating efficiency is not appreciably impaired.

Fig. 1 shows the refrigerating element of the invention applied to a display case refrigerator where its function is to serve in lieu of the ice blocks normally used for cooling food and particularly for causing an efficient circulation of cold air within the interior of the refrigerator.

The display case refrigerator shown in Fig. 1 comprises a base 20 provided with a suitable lining 21 and suitably insulated as with cork-board 22. Glass panels 23 are arranged at the sides and top of the case and preferably with air spaces 24 to serve as insulation.

75 80 85 A top counter portion 25 similar in structure to the bottom is disposed in the center of the top so as to hide the header from view of customers and to furnish additional insulation. The refrigerating element comprising the header, loops and fins is mounted in the center of the interior of the display case as shown in Fig. 1.

90 95 100 Baffles 26 of any suitable material are positioned at either side of the unit and the position of the baffles and distance of the unit from the bottom should be proportioned so as to permit of free circulation of air within the display case. It is apparent that the baffles 26, top section 25 and the central portion of the bottom 21 immediately below the refrigerating element as well as the side walls (not shown) constitute a chilling chamber or cooling unit section and that the refrigerating element or unit when suitably mounted therein, as by brackets, not shown, serves the function normally played by a block of ice.

105 110 115 The arrows in Fig. 1 illustrate the general circulation of the air in a display case equipped with the refrigerating element of the invention. The refrigerating element is placed in the position normally occupied by a block of ice. It is however, much more efficient than ice in that air may circulate unhindered between the parallel fins whereas in a block of ice the circulation is limited to the amount of air which can lap the surfaces of the block.

120 125 130 As shown by the arrows in Fig. 1 the air cooled by the refrigerating element passes through the flues beneath the baffles and travels along the bottom of the food storage sections of the display case, cooling the article there displayed. Shelves or trays or the like may be disposed within the display case as shown diagrammatically by the dotted lines, suitable provision being made for insuring circulation over and around the same such as by spacing the trays from the side walls of the case or by using trays made of screening or the like. The air heated by its contact with the contents of the case passes upward and returns to the chilling chamber by means of the upper flues where it circu-

lates between the channels formed by the fins. While the form of embodiment of the invention as herein disclosed, constitutes a preferred form, it is to be understood that other forms might be adopted, all coming within the scope of the claims which follow.

What is claimed is as follows:

1. A refrigerating element for mechanical refrigerators comprising a header, a plurality of duct loops depending from said header and connected thereto in parallel, said loops being arranged in sets, certain of said sets each comprising loops of vertically depending legs substantially laterally offset from the vertical plane of the header, a fin for each of said sets, the fin of a set being thermally connected to each of the most laterally offset legs, and a set of loops intermediate said sets of finned loops, said latter set including loops having vertically depending legs offset laterally to a lesser degree than said legs of the first set.

2. A refrigerating element for mechanical refrigerators comprising a header, a plurality of duct loops depending from said header and connected thereto in parallel, said loops being arranged in sets, certain of said sets each comprising loops of vertically depending legs substantially laterally offset from the vertical plane of the header, the most laterally offset legs extending in close parallel planes, a fin for each of said sets, the fin of a set being in good contact with one side of one leg on one side of the header and with the other side of the corresponding leg on the opposite side of said header, and a set of loops intermediate said sets of finned loops, said latter set including loops having vertically depending legs offset laterally to a lesser degree than said legs of the first set.

3. A refrigerating element for mechanical refrigerators comprising a header, a plurality of duct loops depending from said header and connected thereto in parallel, said loops being arranged in sets, each set having two loops, each of the loops of one set having two substantially upright legs and a horizontal leg, the horizontal and upright legs of both loops lying in close parallel vertical planes transverse to said header, each loop of said set having one leg offset laterally to a substantial degree from the vertical axis of said header, each loop of another set having a leg laterally offset to a lesser degree than the furthest laterally offset leg of the first set, and a fin attached to the first set in good thermal contact with each leg of said set.

4. A refrigerating element for mechanical refrigerators comprising a header, a plurality of duct loops depending from said header and connected thereto in parallel, said loops being arranged in sets, one set comprising a plurality of duct loops, each having vertical legs depending downwardly in the same

plane and on opposite sides of the header, one of said legs of each loop being laterally offset a substantial amount from the vertical axis of the header and the other leg of each loop depending substantially adjacent the header, and another set comprising loops arranged in close parallel planes and including vertical legs likewise depending downwardly in the same plane and on opposite sides of the header but offset laterally to a lesser degree than the furthest offset legs of said first set, a plurality of fins, each fin comprising a metal sheet lying in a parallel plane intermediate the planes of all of the loops of one of the first sets and attached to said loops in good thermal contact.

5. A refrigerating element for mechanical refrigerators comprising a header, a plurality of parallel air circulating channels depending vertically from said header, and extending substantially to equal distances to both sides and underneath the header, said channels being formed of duct loops depending from said header and arranged in sets and provided with fins, one fin being attached to a set of dependent loops lying in parallel planes, said loops of a set each having a leg depending vertically substantially adjacent the header and another leg laterally offset to a substantial degree from said header, the space between said channels being occupied by a similar set of duct loops of which the offset leg does not extend laterally to the same extent as the finned sets of legs.

6. A refrigerating element for mechanical refrigerators comprising a header, a plurality of parallel air circulating channels depending vertically from said header, and extending substantially to equal distances to both sides and underneath the header, said channels being formed of duct loops depending from said header and provided with fins, one fin being attached to a plurality of depending loops lying in parallel planes, the space between said air channels being occupied by similar depending duct loops not provided with fins.

7. A cooling unit for mechanical refrigerators comprising a plurality of sets of duct loops, certain of said sets being each provided with a fin and certain other of said sets being without fins, the loops of the finned set each including a plurality of vertically extending legs, the fin of the set being thermally connected with at least three of the vertical legs of the set, said certain other sets being interposed between and spaced from the finned sets.

8. A cooling unit for mechanical refrigerators comprising a plurality of sets of ducts, certain of said sets being each provided with a fin and certain other of said sets being without fins, the ducts of the finned sets being fashioned as loops, each having a plurality of

vertically extending legs and each of said finned sets including a plurality of loops, the fin of the set being thermally connected with at least three of the vertical legs of the set, said 5 certain other sets being interposed between and spaced from the finned sets.

9. A cooling unit for mechanical refrigerators comprising a plurality of sets of ducts, each of said sets including at least three vertically extending legs, a fin for each of said sets thermally connected with at least three of said legs, and ducts without fins interposed between and spaced from the finned sets.

15 10. A cooling unit for mechanical refrigerators comprising a plurality of sets of ducts, each of said sets including at least three vertically extending legs, a fin for each of said sets thermally connected with at least three of 20 said legs, said ducts being spaced along the fin, and ducts without fins interposed between and spaced from the finned sets.

11. A cooling unit for mechanical refrigerators comprising a plurality of sets of ducts, 25 each of said sets including at least three vertically extending legs, fin means for each set thermally connected with at least three legs of the set, and ducts without fins interposed between and spaced from the finned sets.

30 12. A refrigerating element for mechanical refrigerators comprising an elongated header, a plurality of sets of duct loops connected with the header along the length thereof in parallel circuit relation, each provided with a fin, a plurality of ducts without fins connected with the header along the length of the header and alternating with the first sets, the 35 loops of the finned sets each having a plurality of vertical extending legs, said fin being thermally connected to a plurality of legs of each loop in the set.

13. A refrigerating element for mechanical refrigerators comprising an elongated header, a plurality of sets of duct loops connected with the header along the length thereof in parallel circuit relation, each provided with a fin, a plurality of ducts without fins connected with the header along the length of the header and alternating with the first sets, 45 the loops of the finned sets each having a plurality of vertical extending legs, one leg of each set being more laterally offset from a vertical plane of the header than its other leg, said fin being thermally connected to both legs of each loop of a set.

14. A refrigerating element for mechanical refrigerators comprising an elongated header, a plurality of sets of duct loops connected with the header along the length thereof in parallel circuit relation, each provided with fin means, a plurality of ducts without fins connected with the header along the length of the header and alternating with the first sets, the loops of the finned sets each 50 having a plurality of vertical extending legs,

said fin means being thermally connected to a plurality of legs of each loop in the set.

In testimony whereof I hereto affix my signature.
